CLAIM

The combined back scrubber and back scratcher with removable sponge element, substantially as shown and described.

DESCRIPTION

FIG. 1 is a front elevational view of a combined back scrubber and back scratcher, showing my new design; FIG. 2 is a side elevational view thereof; FIG. 3 is a front elevational view of the handle with the sponge removed; FIG. 4 is a sectional view taken along line 4—4 of FIG. 3.
